UNITED STATES PATENT OFFICE.

JULIUS JASPER, OF NEW YORK, N. Y., ASSIGNOR TO THE J. HENRY PETERS COMPANY, OF SAME PLACE.

DESIGN FOR A SKIRT-BINDING.

SPECIFICATION forming part of Design No. 34,300, dated March 26, 1901.

Application filed February 26, 1901. Serial No. 49,003. Term of patent 7 years.

To all whom it may concern:

Be it known that I, JULIUS JASPER, a citizen of the United States, and a resident of the borough of Manhattan, in the city and State of New York, have invented and produced a new and original Design for a Skirt-Binding, of which the following is a specification.

The essential feature of my design consists in a skirt-binding having a brush pendent from one edge thereof, three series of short columns extending longitudinally along the head, one in proximity to the brush, another a short distance therefrom, and a third in proximity to the opposite edge of the binding, a broken zigzag line intermediate of the two longitudinal series of columns nearest the brush, and a mottled effect intermediate of the series of short columns at the opposite edge and the intermediate series.

In the accompanying drawing, which represents a piece of the binding in elevation, *a* represents the brush; *b c d*, the series of columns extending longitudinally along the head; *e*, the broken zigzag line intermediate of the series of columns *b* and *c*, and *f* the mottled effect intermediate of the longitudinal series of columns *c* and *d*.

What I claim is—

The design for a skirt-binding, substantially as herein shown and described.

In testimony that I claim the foregoing as my invention I have signed my name, in presence of two witnesses, this 20th day of February, 1901.

JULIUS JASPER.
